UNITED STATES PATENT OFFICE.

JOHN OPELZ, OF CLEVELAND, OHIO, ASSIGNOR OF ONE-THIRD TO FRANK ALTMAYER,
OF CLEVELAND, OHIO.

ROOFING-TILE.

1,092,799.

Specification of Letters Patent.

Patented Apr. 7, 1914.

Application filed April 10, 1913. Serial No. 760,257.

To all whom it may concern:

Be it known that I, JOHN OPELZ, a subject of the Emperor of Austria-Hungary, residing at Cleveland, in the county of 5 Cuyahoga and State of Ohio, have invented certain new and useful Improvements in Roofing-Tile, of which the following is a specification.

This invention relates to roofing tile, and particularly to that class thereof in which the tile when laid will interlock to form close joints at the lapped edges, means being provided to interlock the tile at the side edges as well as at the top and bottom ends, 15 where the edges and the ends overlap respectively, the object being to produce a tile which will be water proof and without leaky joints.

A further object of the invention is to 20 provide improved means for fastening the tile to the rafters.

In the accompanying drawings—Figure 1 is a top plan view of some of the tile as laid on a roof. Fig. 2 is a bottom view of 25 some of the assembled tile. Fig. 3 is a cross section on the line 3—3 of Fig. 1. Fig. 4 is a longitudinal section.

The tile will preferably be constructed of 30 molded material, but may be produced in metal or other material if desired. Each tile is substantially rectangular in outline, and on the upper face thereof, at one edge, it has a pair of ribs 9, extending lengthwise, and producing grooves therebetween. At 35 the opposite edge, the under side of the tile has a corresponding pair of ribs 10, the thickness of the tile being reduced at each edge so that said edges may be overlapped, and when they are lapped the ribs 10 fit between the ribs 9 to make a tight joint at the 40 edges. The upper surface of the tile may also be grooved as indicated at 11, and the

lower surface provided with depressions 12, for the sake of lightness and economy of material. On the upper surface, near the 45 upper edge, each tile has ribs 13 extending crosswise and spaced apart to form a groove sufficiently wide to receive the corresponding rib 14 on the lower end and underside of the tile next above, and at the upper end each 50 tile has a notch 8 at about the middle thereof through which extends the lug 7^a located at the lower corner and underside of the tile next above, and beside each notch the tile has a downwardly extending lug 7. When 55 the tile are laid in courses these lugs are located beside each other, and each lug has a hole through the same, which holes register to receive a pin 15 which holds the tiles together and thereby clamps the successive 60 courses to each other, and the pin or nail may extend into a rafter 16 to hold the roof in place.

The notches and lugs exactly position the various tiles with respect to each other and 65 enable the roof to be quickly laid, and the interlocking ribs and grooves, as well as the lugs fastened together, prevent any shift or movement of the various tiles and insures a tight and water proof roof. 70

What I claim as new is:

A roofing tile having a notch at the middle of one end and a depending lug beside said notch, and also having a depending lug at the corner of the opposite end adapted to 75 fit through the notch and beside the lug of an adjacent tile, and means to fasten together the lugs of adjacent tiles.

In testimony whereof, I do affix my signature in presence of two witnesses.

JOHN OPELZ.
